UNITED STATES PATENT OFFICE

STEPHEN N. COLEMAN, OF SYLACAUGA, ALABAMA

SPRING SUPPORT FOR LADIES' SHOES

Application filed March 18, 1930. Serial No. 436,845.

This invention aims to provide a novel spring heel support or reinforcement for women's shoes, the construction being such that the article may be driven between the heel and the sole of the shoe, and clear the nails that hold the heel in place, the device being so constituted that the thinned forward edge of the heel will not be broken when the device is in use.

10 It is within the province of the disclosure to improve generally and to enhance the utility of devices of that type to which the present invention appertains.

With the above and other objects in view, 15 which will appear as the description proceeds, the invention resides in the combination and arrangement of parts and in the details of construction hereinafter described and claimed, it being understood that changes 20 may be made in the precise embodiment of the invention herein disclosed, within the scope of what is claimed, without departing from the spirit of the invention.

In the accompanying drawings:—

25 Figure 1 shows in side elevation, a device constructed in accordance with the invention, mounted in a woman's shoe, parts being in section;

30 Figure 2 is a bottom plan of the shoe with the device forming the subject matter of this application mounted therein, parts being broken away;

Figure 3 is a plan of the article per se;

Figure 4 is an end elevation of the article 35 shown in Figure 3.

The numeral 1 marks a woman's shoe including a sole 2 to which is nailed a heel 3 having a thinned forward edge 14.

In carrying out the invention, there is provided a metal plate 4 preferably made of spring steel, including a body 5 of approximately rectangular outline, the body 5 being curved cross-wise, as shown at 6, so as to shape itself to the transverse curvature of the sole 45 of the shoe immediately in advance of the heel 3. The plate 4 includes an entering portion 7, the edges of which converge to form a single point 8, located in the longitudinal axis of the plate 4. The plate is broadened, as shown at 9, where the entering

portion 7 joins the body 5. There are openings 10 in the body 5, and these openings are adapted to receive securing elements 11 which, entering the sole of the shoe, hold the plate in place. 55

The point 8 may be driven between the heel 3 and the sole 2 of the shoe and will clear the nails that hold the heel of the shoe in place. Because the metal plate 4 has the single point 8, the plate will drive straight 60 back above the heel 3, and will hold it in place. The broadened part 9 of the plate 4 comes immediately under the thinned edge 14 of the heel 3, and thus the thinned edge 14 is given an increased lateral support, and 65 the thinned edge will not be likely to be broken. The usual leather strip 12 is carried backwardly over the exposed portion of the plate 4, to hide it completely, the strip being secured to the forward surface of the 70 heel 3 in the usual way.

Having thus described the invention, what is claimed is:—

The combination with an article of footwear comprising a sole, and a heel having a 75 thinned, upper, forward edge, of a plate having a body and an entering portion, the entering portion having a single point disposed in the longitudinal axis of the plate and located between the heel and the sole, the 80 plate being broadened at the place where the entering portion is joined to the body, the broadened part of the plate being located immediately above the said thinned edge of the heel, to support said thinned edge, the forward edge of the body of the plate being straight, at right angles to the longitudinal axis of the plate, symmetrical with respect to said axis, and almost as long as the width of the broadened part of the plate, to facilitate 85 the driving of the entering portion between the heel and the sole. 90

In testimony that I claim the foregoing as my own, I have hereto affixed my signature.

STEPHEN N. COLEMAN. 95
